US0D1045787S

(12) **United States Design Patent** (10) **Patent No.:** **US D1,045,787 S**
(45) **Date of Patent:** **** Oct. 8, 2024**

(54) **MOBILE POWER SUPPLY**

(71) Applicant: **Shenzhen Xianyang Innovation Technology Co., Ltd.**, Shenzhen (CN)
(72) Inventor: **Huiyi Ke**, Shenzhen (CN)
(73) Assignee: **Shenzhen Xianyang Innovation Technology Co., Ltd.**, Shenzhen (CN)

(**) Term: **15 Years**

(21) Appl. No.: **29/941,207**

(22) Filed: **May 8, 2024**

(51) LOC (14) Cl. **13-02**
(52) U.S. Cl.

USPC **D13/108**

(57) **CLAIM**

The ornamental design for a mobile power supply, as shown and described.

DESCRIPTION

FIG. 1 is a front, right and top perspective view of a mobile power supply, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and bottom perspective view of the mobile power supply in a usable state.

FIG. 10 is an enlarged view of detail 10 in FIG. 1.

FIG. 11 is an enlarged view of detail 11 in FIG. 5; and, FIG. 12 is an enlarged view of detail 12 in FIG. 7.

The dashed broken lines depict portions of the mobile power supply that form no part of the claimed design.

The dot-dash broken lines in FIGS. 1, 5, 7, 10, 11 and 12 depict the boundaries of the enlargements that form no part of the claimed design.

1 Claim, 12 Drawing Sheets
